UNITED STATES PATENT OFFICE.

PATRICK J. MADIGAN, OF CHICAGO, ILLINOIS.

COMBINED DOOR, LOCK, AND INDICATOR FOR CARRIERS USED IN PNEUMATIC TUBES.

No. 808,768.

Specification of Letters *as filed*.

Patented Jan. 2, 1906.

Application filed February 25, 1905. Serial No. 247,309.

To all whom it may concern:

Be it known that I, PATRICK J. MADIGAN, a citizen of the United States, residing at 6635 Langley avenue, in the city of Chicago, in the county of Cook and State of Illinois, have invented a new and useful Improvement in a Combined Door, Lock, and Indicator for Carriers Used in Pneumatic Tubes, of which the following is a specification.

10 My invention relates to the combination of doors, locks, and indicators of that class of carriers used for the transmission of mail and other matter through pneumatic tubes, the doors of which are required to be locked 15 while in transmission to different stations on the line of the tube.

The object of my invention is to provide a combination door, lock, and indicator for the carrier which can be closed, locked, and indication set by the movement of the handle; that when closed, locked, and set cannot be forced open by the concussive, rotative, or centrifugal force developed in the movement of the carrier through the tube; that can be 25 instantly closed, locked, set, and unlocked with the hand; that when closed, locked, and set will indicate the station at which the contents of the carrier is to be received, and also indicates that it is either the only carrier or 30 is the last of a number of carriers destined for one particular station. The manner in which I accomplish these objects is set forth in the following specification and illustrated in the accompanying drawings, in which—

35 Figure 1 is a face view of the door, handle, and indicator in the positions when the door is closed and bolted. Fig. 2 is an inside view of the door, showing the arrangement of the bolts and connecting mechanism, the dotted 40 lines showing the position of the bolts and other parts when the door is unlocked and open. Fig. 3 is a central vertical sectional view on the line 1 1, Fig. 1, the parts being shown in the bolted position. Fig. 4 is a side 45 view of part of the carrier with the door closed and locked.

The carrier A is of the regular cylindrical form provided with two bearing-rings B, only one of which is shown. At one end of this 50 carrier is a door C, permanently connected with the carrier by a hinge-joint D. The back E of the door is in the form of a circular shallow pan. The raised part F of the back

E is adapted to fit inside of the carrier, as shown by the dotted line F I in Fig. 4, and 55 is flanged at the edge G to cover and fit the end of the carrier, as shown in Fig. 4. Arranged within this back are three bolts H, supported in bearings I and free to slide therein. The ends of each of these bolts extend through suitable holes in the raised part 60 F of the back E. Two of these bolts are each pivotally connected to bell-crank levers J. Each of these levers are held on the pivot-studs K, affixed in the back E. The third 65 bolt is part of a sliding bar L, which extends across the center of the back E. On the top of this bar is a vertical post M. On the under side of the bar is a transverse channel N. This channel is adapted to receive the ends 70 O of the levers J, as shown in Fig. 2. A projection P on the end of the sliding bar L is adapted to strike the hinge-joint D and act as a stop.

Affixed in the back E are four supports R, 75 having threaded holes and adapted to form a base for the cover S, which is firmly secured by screws held in said supports R. In the center of this cover is an oblong aperture through which the post M projects. This 80 aperture is adapted in width to fit said post and in length to limit the sliding movement of the post M, which is free to be moved back and forth in said aperture, and thereby permits the bolts H to be withdrawn from the 85 bolt-holes in the carrier when the door is to be opened and to be forced into said carrier when the door is shut. On the face of the cover S is a lug T and near it a lock-pin U, the purposes of which will be described hereinafter. Near the outer edge of the cover S are two sets of figures, the left-side figures being indicated with a capital X, and is there-by designated as the "X side" of the cover.

Attached to the post M, which projects 95 through its center, is the handle V, provided with a projected top ring V'. On the bottom of the handle V is a circular washer V², and resting on this washer is a flat spring V³, having an aperture adapted to fit the flat 100 sides of the post M. This spring is curved so that the ends rest on said washer, the center part being raised some distance above the washer. Through a hole in the post M a cotter-pin V⁴ is passed and made fast. The 105 spring V³ is compressed between this cotter-

pin and the washer V^2 , the pressure of the spring forcing the handle down upon the cover S , the curve of the spring permitting the handle to be raised from the cover, this movement, however, being limited by the curve of the spring and the cotter-pin. Thus attached, the handle is free to be lifted slightly off the cover and to be rotated to the right or left, the post M forming the pivot.

10 In the base V^5 of the handle are a number of holes V^6 , corresponding in number and radial position with the figures on the cover. Each of these holes is adapted to fit on the lock-pin U on the cover S . Affixed to the base V^5 is a finger-point V^7 , adapted to pass over lug T and point to each of the figures on the cover as the handle is rotated. Underneath this finger-point on the base V^5 is an open slot V^8 , adapted to receive the lug T and to

15 permit the handle to be moved toward the hinged joint D , carrying with it the post M and sliding bar L , thereby actuating the levers J and drawing the bolts H into the position required to open or close the door.

20 25 When in that position, the slot V^8 engages the lug T and locks the handle so it cannot be revolved. When the door is closed, the handle is pulled down to the center. This movement operates the bar L and levers J , there-

25 30 by forcing out the bolts H into the carrier, and bolts the door. To lock the door after it is bolted, the handle is grasped by the hand, the fingers extending over the projecting ring V' , above the finger-point V^7 , the

35 35 palm of the hand resting on the other side of said ring as a fulcrum. A lifting pressure is then exerted through the fingers and the pointer, and that part of the base of the handle to which it is affixed is lifted off the lock-

40 45 pin U and is then turned to the right or to the left, as shown by the dotted finger-points in Fig. 1. When the handle is so turned, the finger-point is opposite the desired transfer, the lifting pressure of the fingers is released, and the force of the spring V^3 presses the handle down onto the cover and over the lock-pin U , which is then engaged in one of the holes in its base, and thereby locks the door. When the finger points to any figure on the

50 55 right-hand side of the door, it indicates the number of the station at which its contents is to be received and that one or more carriers are to follow the first. When the finger is turned to a figure on the left side of the door, as shown by the dotted lines in Fig. 1, it indicates the station at which it is to be received and that it is either the only carrier to be received at that station or that it is the last of a number destined for that station.

60 65 To unlock and open the door, the handle is grasped as before, the lifting pressure applied, and the handle revolved until the fin-

ger-point is over the lug T , at which point only can the door be unlocked, as the base V^5 of the handles cannot be lifted above the lug T , and therefore cannot be forced toward the hinged joint till the slot V^8 is in position to pass the lug.

What I claim, and desire to secure by Letters Patent, is—

1. In combination with a carrier of the kind described, a door C pivotally attached thereto; a locking mechanism in said door consisting of the bolts H , levers J , sliding bar L , a handle V attached to said bar and a lug T on the cover of said door; an indicator mechanism on said door consisting of a handle V revolvably supported on the post M on the sliding bar L ; a series of holes V^6 in the base of said handle, and a locking-pin U on the cover of said door adapted to be engaged in said holes, a pointer V^7 extending radially from the base of said handle, and a cover S having a series of figures thereon, substantially as described and for the purposes specified.

2. In a device of the kind described, the combination of a door C having parts E and S and being adapted to be pivotally attached to a carrier A ; bolts H , connecting-levers J and operating-bar L having a post M , supported in said door; a handle V revolvably supported on said post; a base V^5 forming part of said handle and having a slot V^8 , a lug T on the part S of said door adapted to be engaged by said base and to enter said slot; a series of holes in said base and a pin U on the part S adapted to enter said holes and a pointer V^7 forming part of said base of said handle, substantially as described and for the purposes specified.

3. In a device of the kind described, the combination of a door C pivotally attached to a carrier A said door being formed of a main body E and a cover S ; with a pair of bolts H , connecting-levers J , sliding bar L having a post M and a handle V revolvably attached to said post; said handle having a base provided with a slot and series of holes; a lug on said cover adapted to engage said base, and a pin adapted to enter said holes in said base, substantially as described and for the purposes specified.

4. In a device of the kind described the combination of a door C pivotally attached to a carrier A , said door being formed of the parts E and S ; and bolts H , levers J and a sliding bar L having a post M ; with a handle adapted to be attached to said post and revolvble thereon, said handle having a base with a slot and series of holes therein; and a lug T , and pin U adapted to be engaged by said base; and a pointer V^7 , substantially as described and for the purposes specified.

5. In a device of the kind described, the combination of a door C formed of parts E and S, the part S having a lug T, lock-pin U and series of radial figures; and bolts H, lever 5 J, sliding bar L having a post M and handle V; with a base V⁵ forming part of said handle, said base having a slot and series of holes and a pointer substantially as described and for the purposes specified.
